(57) **CLAIM**

The ornamental design for a control and programming unit for robots, as shown and described.

DESCRIPTION

FIG. 1 is a top, side and end perspective view of a control and programming unit for robots, showing my new design;

FIG. 2 is a view similar to FIG. 1 but showing the side opposite that shown in FIG. 1;

FIG. 3 is a side elevational view thereof;

FIG. 4 is an end elevational view thereof from the left of FIG. 3;

FIG. 5 is an end elevational view thereof from the right of FIG. 3;

FIG. 6 is a top plan view thereof; and,

FIG. 7 is a bottom plan view thereof.

The broken lines are for illustrative purposes only and form no part of the claimed design.
